CLAIM

The ornamental design for a bottom portion of a golf club head, as shown and described.

DESCRIPTION

FIG. 1 is a perspective view of a golf club head held upside down and showing my new design;

FIG. 2 is a front elevational of the golf club head;

FIG. 3 is a left side elevational view thereof;

FIG. 4 is a right side elevational view thereof;

FIG. 5 is a rear elevational view thereof; and,

FIG. 6 is a plan view of the golf club head.

The broken line showing of the golf club head is for illustrative purposes only and forms no part of the claimed design.
